UNITED STATES PATENT OFFICE.

CARL RASMUSSEN, OF BRUNSWICK, GERMANY.

CALCULATING-MACHINE.

1,175,810.

Specification of Letters Patent.

Patented Mar. 14, 1916.

Application filed November 25, 1914. Serial No. 874,010.

To all whom it may concern:

Be it known that I, CARL RASMUSSEN, engineer, subject of the King of Norway, residing at Brunswick, Germany, have invented certain new and useful Improvements in Calculating-Machines, of which the following is a specification.

My invention relates to improvements in carrying mechanisms such as are used in calculating machines and the like.

More particularly my invention relates to machines of this class in which a setting mechanism and a registering mechanism are provided which are movable relatively to each other. In calculating machines the setting mechanism is ordinarily mounted on the stationary frame of the machine, while the registering mechanism is mounted on a slide which is shiftable along the setting mechanism.

The object of the improvements is to provide a carrying mechanism for machines of this class in which all the operative parts are movable with the registering mechanism.

With this object in view my invention consists in the matters to be described hereinafter and particularly pointed out in the appended claims.

For the purpose of explaining the invention an example embodying the same has been shown in the accompanying drawing, in which the same letters of reference have been used in all the views to indicate corresponding parts.

In said drawing—Figure 1, is a vertical cross-section of the calculating machine, and Fig. 2, is a partial plan view of the same with the cover of the casing partly removed.

For the purpose of explaining the invention reference will be made to a calculating machine of the type shown and described for example in the patent of the United States No. 1,100,689 granted to me June 16, 1914. But I wish it to be understood that my invention is not limited to the construction shown in the drawing, nor to the use in combination with a calculating machine.

Referring to the drawing, the calculating machine consists of a setting mechanism which comprises setting disks a secured to a rotary shaft q and provided with radially shiftable teeth b , and of a registering mechanism which comprises numeral wheels k and gear wheels k^2 connected one with each of the numeral wheels. The registering mechanism is mounted on a slide or carriage k^3

which is adapted to be shifted along the setting mechanism. The values set on the setting disks by shifting the proper number of teeth b into operative positions are transmitted to the numeral wheels through intermediate gear wheels n which are mounted on the slide k^3 .

The numeral wheels k or the gear wheels k^2 are each provided with a nose k^1 which is located in such a position that when the corresponding numeral wheel passes from its "nine" position to its "zero" position a rocker h is rocked which is mounted on a shaft i . The said rocker is made integral with an arm h^1 which carries a block g having two cam faces directed to opposite sides. The said block is located at the side of a disk f which is provided with a radially shiftable tooth e (or where the machine is constructed for operation in both directions with two teeth e one for multiplication and the other one for division). All the disks are rotated from the machine crank by a mechanism which will be described hereinafter, and when a disk is thus rotated in which the tooth e has been shifted into operative position, the intermediate gear wheel coöperating with the numeral wheel of the next higher order is advanced the distance which corresponds to one value, and this rotation is transmitted to the coöperating numeral wheel. The tooth e is provided with a nose e^1 which projects laterally therefrom and into position for engagement with the block g , so that it rides on the latter when the block has been set by the nose k^1 in operative position.

After the rocker h , h^1 has been rocked by the tooth e^1 into operative position, it is held in such position, until the carrying operation is completed. For this purpose the rocker is provided with a shoulder h^2 which is adapted to be engaged by a spring d when the rocker has been locked. The spring locks the rocker in rocked position, so that the block g can not return into inoperative position before carrying is completed.

All the springs d which coöperate with each one of the rockers h are secured to a rock shaft m which is normally held by a spring in the position in which the springs d are in positions for locking the rockers h . At the end of the carrying operation the said shaft is rocked so as to retract all the springs d away from the rockers h and per-

mit the same to drop with the blocks g into inoperative positions. In the preferred form of the invention shown in the drawing the shaft m is automatically rocked 5 through mechanism connected with the machine crank and the shaft g . As shown a cam disk c' is mounted on the shaft c , which is adapted to strike a lever m^1 secured to the shaft m so as to rock the same with the 10 springs d away from the rockers h .

As stated before, the carrying operation includes rotation of the shaft c which carries the disks f , and such rotation must be performed in any position of the slide k^3 15 relative to the stationary casing. To effect this, a shaft o is mounted on the stationary part n^1 of the machine near the slide k^3 and parallel to the direction of the movement of the slide indicated in Fig. 2 by the arrow α . 20 The shaft o is adapted to be rotated from the machine crank q through the intermediary of gear wheels p , p^1 , and p^2 . On the shaft o a gear wheel r is mounted which takes part in the rotation of the shaft and 25 is longitudinally shiftable thereon, and the said gear wheel is connected with a gear wheel r^2 mounted on the shaft c through an intermediate gear wheel r^1 mounted on the slide k^3 . The gear wheels r , r^1 , and r^2 remain 30 always in mesh with one another, for which purpose the hub of the gear wheel r is so connected with the slide k^3 by means of a bifurcated member s , that the gear wheel r is carried along on the shaft o when 35 the slide is shifted.

I claim herein as my invention:

1. In a mechanism of the class described, the combination with a movable registering mechanism and its numeral wheels, and a 40 stationary mechanism for transmitting values thereto, of carrying members movable with the registering mechanism, means controlled by and movable with the numeral

wheels to set the carrying members in operative positions, a stationary rotary shaft, 45 a gear wheel on said shaft taking part in the rotation thereof and longitudinally shiftable thereon and operatively connected with said carrying members, means to hold said gear wheel in operative position relatively to the 50 carrying members when shifting the registering mechanism, and an operative connection between the gear wheel and the operating means for the setting mechanism.

2. In a mechanism of the class described, 55 the combination with a registering mechanism and its numeral wheels; a stationary mechanism for transmitting values thereto; said registering mechanism being shiftable relative to said stationary mechanism; operating means for the said stationary value transmitting mechanism; of carrying members shiftable with the registering mechanism, one of said members for each numeral wheel and operated thereby for actuating 60 the next numeral wheel; a stationary rotatable shaft on the stationary mechanism; a gear wheel rotatable with and longitudinally shiftable upon said shaft, said wheel being operatively connected with said carrying members; means for holding said gear wheels in operative position with the carrying members and for shifting the same therewith, when said registering mechanism is shifted relatively to the stationary mechanism; and an operative connection between 65 said stationary shaft and said operating means for the value transmitting mechanism. 70

In testimony whereof I have hereunto set my hand in presence of two subscribing 80 witnesses:

CARL RASMUSSEN.
